UNITED STATES PATENT OFFICE.

JULIAN BERNHARDT, OF SAN FRANCISCO, CALIFORNIA

COMBINED BOOK-MARK AND CORNER-PROTECTOR

964,895.

Specification of Letters Patent. Patented July 19, 1910.

Application filed July 24, 1909. Serial No. 509,352.

To all whom it may concern:

Be it known that I, JULIAN BERNHARDT, a citizen of the United States, residing at San Francisco, in the county of San Francisco and State of California, have invented new and useful Improvements in Combined Book-Marks and Corner-Protectors, of which the following is a specification.

This invention relates to a combined book 10 mark and page or corner protector.

The object of the invention is to provide a simple, efficient and inexpensive device for covering and protecting the corners of the covers or leaves of a book to protect the 15 same from injury, and which is also adapted to perform the function of a book mark.

The invention consists of the features of construction, combination and arrangement of parts hereinafter fully described and 20 claimed, reference being had to the accompanying drawing, in which:

Figure 1 is a perspective view of a portion of an open book showing the application 25 of the invention. Fig. 2 is a top plan view of the protector. Fig. 3 is a transverse section on line 3—3 of Fig. 2. Fig. 4 is a bottom plan view of the protector.

As shown in the drawing, the protector comprises a triangular body, top portion or 30 plate 1 provided with correspondingly shaped bottom flanges or plates 2 extending inwardly from the side edges thereof and having their adjacent inner edges spaced apart in parallel relation or substantially so. 35 These bottom flanges or plates are formed with extensions 3, similar in shape thereto, which project in corresponding relation beyond the front or basal edge 4 of the said body or top plate 1. Each flange and its 40 extension thus forms a triangular base piece whose sides extend at right angles to the respective sides of the top plate. The device as thus constructed is formed from a suitable blank of sheet metal, preferably spring 45 sheet metal, although it may be made of celluloid or other suitable material, the flanges forming with the body plate a triangular pocket to receive the corner of a cover or leaf or corners of a plurality of leaves of a book, and also serving as jaws to clamp the 50 cover or leaf against the body plate.

Preferably the connecting edges of the top plate 1 and bottom flanges 2 are made in partially circular form to provide spring 55 loops 5, from which the flanges incline inwardly and upwardly toward the top plate,

with which their inner free edges normally contact, as shown in Fig. 3, by which construction the said flanges or jaws are adapted to have a greater range of resilient action and capacity to bear with greater force 60 against the inserted sheet or sheets.

The device may be used in an obvious manner as a protector for the corners of the covers of a book. It may also be used as a protector for the lower corner edges of the exposed leaves of a book of the kind normally kept open at current pages, such as a hotel register, log book, account book, etc., to prevent such corners from becoming soiled or 70 torn from frequent handling. In the latter named use it will, of course, be understood that for additional security each protector used may be engaged with the corner edges of the top page and one or more underlying 75 pages, and that in this connection it will serve as a book mark to enable the book, when closed, to be at once opened at the proper page.

In applying the device to the corners of 80 one or more leaves, the corner portions 6 and 7 are engaged by the thumb and forefinger of the hand and the device manipulated to slip the extensions 3 of the protector beneath the leaf or leaves until the corner or 85 corners thereof is or are in line with the space between such extensions and the center of the front edge of the top plate 1, when the leaf or leaves are held firmly and the device slid onto the same, whereby the corner or corners of the leaf or leaves is or are inserted between the top plate and flanges or 90 jaws and clamped by the latter against the former. In removing the device, the corners 95 6 and 7 are grasped in like manner and the protector forcibly slid off.

By reason of the peculiar construction of the protector several advantages are obtained. The extensions 3 of the bottom flanges 2 not only admit of the more ready 100 insertion of the device between leaves, but add weight beyond the clamping point to insure a firmer engagement of the protector with the leaves and to hold the exposed leaf down flat. According to the number and 105 thickness of the leaves engaged, it will be understood that the flanges 2 will yield to a greater or less extent, as shown in dotted lines in Fig. 3, the loops 5 permitting a maximum range of movement so that a number 110 of leaves may be inserted and clamped firmly, the clamping action increasing pro-

gressively with the number of leaves. Hence it will be seen that my invention provides a protector which is simple of construction and effective for its intended purpose.

5 Having thus fully described the invention, what is claimed as new; is:—

1. A corner protector formed from a single strip of material and comprising a triangular top plate, triangular bottom flanges 10 extending inwardly from the side edges of the top plate, and triangular extensions from said flanges projecting beyond the front edge of the top plate, said flanges and extensions forming triangular bottom plates arranged in parallel relation to the top plate and having their inner edges spaced apart throughout their length and arranged at right angles to said front edge of the top plate.
- 15 2. A corner protector formed from a single strip of material and comprising a tri-

angular top plate, triangular bottom flanges extending inwardly from the side edges of the top plate and connected at their outer edges by partially circular spring loops with said side edges of the top plate, and triangular extensions from said flanges projecting beyond the forward edge of the top plate, said flanges and extensions forming triangular bottom plates arranged in parallel relation to the top plate and having their inner edges spaced apart throughout their length and arranged at right angles to said front edge of the top plate.

25 In testimony whereof I affix my signature in presence of two witnesses.

JULIAN BERNHARDT.
